UNITED STATES PATENT OFFICE.

ARTHUR P. CURTIS, OF FULTON, NEW YORK, ASSIGNOR TO THE HUNTER ARMS CO., OF FULTON, NEW YORK, A CORPORATION OF NEW YORK.

FIREARM.

1,159,183.

Specification of Letters Patent.

Patented Nov. 2, 1915.

Application filed March 28, 1913. Serial No. 757,327.

To all whom it may concern:

Be it known that I, ARTHUR P. CURTIS, a citizen of the United States, and a resident of Fulton, in the county of Oswego and State of New York, have invented a new and useful Firearm, of which the following is a specification.

This invention relates to firearms and has for its object the production of a particularly simple and efficient construction of firing pin and means for retaining the firing pin from displacement; and the invention consists in the combinations and constructions hereinafter set forth and claimed.

In describing this invention reference is had to the accompanying drawings in which like characters designate corresponding parts in all the views.

Figure 1 is a side elevation, partly broken away and partly in section, of one form of my firing pin and contiguous parts. Fig. 2 is a section on line "—A—A—", Fig. 1, the firing pin being shown in elevation. Fig. 3 is an elevation of the removable side or lock plate.

I have here illustrated my invention as embodied in a break-down shot gun and in the drawing, 1 designates the frame and 2 the barrel which is hinged to the frame in the usual manner, the frame including the usual block 3 located at the rear of the barrel and formed with a lengthwise passage 4 which opens through its front and rear faces.

5 is the firing pin slidable in the passage 4. 6 is the removable side or lock plate held in position by suitable fastening means as screws, this firing pin being arranged and shaped to be held in position by the side plate.

40 The side or lock plate 6 is arranged with its outer face flush with the outer face of the frame, Fig. 2, in the usual manner, and as here shown the side plate is formed with an edge portion which extends across the rear 45 end of the passage 4 and partly closes the same, as seen in Fig. 2, and which coacts with the body of the firing pin to prevent the same from displacement.

As here illustrated the side plate 6 is 50 formed with an upwardly extending portion 7 closing the space of the frame in the rear of the block 3, this portion having a forwardly facing edge 8 which extends across and partly closes the rear end of the passage 4.

Preferably the passage 4 includes a cylindrical portion and a reduced tapered front portion, and the firing pin 5 includes a cylindrical body slidable in the cylindrical portion of the passage 4, and a tapered front 60 portion or point 9, movable through the tapered front portion of the passage 4, and the edge 8 of the side plate 6 engages the rear face of the cylindrical body portion of the firing pin 5. The firing pin is also provided 65 with a rearwardly extending reduced portion 10 arranged to receive the blow of the hammer 11, said portion 10 lying at the inner side of the side plate and projecting to the rear of the edge 8 of the side plate. 70 The passage 4 is shown as inclined upwardly toward its front end out of a horizontal line. In guns of different sizes that is guns having barrels of larger bore the passage 4 will be less inclined or horizontal. 75

The constructions and arrangements herein described are particularly simple and durable and provide for the ready removal of the firing pin upon the removal of the side plate.

What I claim is:

1. In a firearm, a frame formed with a passage extending forwardly and rearwardly and open at its opposite ends, a firing pin movable in the passage, and a removable side plate, the firing pin being arranged to be held from displacement out of the passage by the side plate, substantially as and for the purpose described. 85

2. In a firearm, a frame formed with a lengthwise passage open at its opposite ends, a firing pin movable in the passage and formed with a rearwardly facing shoulder, and a side plate having a portion projecting in the path of the shoulder for normally preventing displacement of the firing pin, substantially as and for the purpose specified. 90

3. In a firearm, a frame formed with a lengthwise passage open at its opposite ends, 100 a firing pin slidable in the passage, and a removable side plate, the passage being arranged so that an edge portion of the side plate extends across and partly closes the rear end thereof, and thereby retains the 105 firing pin in the passage, substantially as and for the purpose set forth.

4. In a firearm, a frame formed with a lengthwise passage open at its opposite ends, a firing pin movable in the passage, and a 110

side plate having a forwardly facing edge, the passage being arranged so that its rear end is partly closed by said edge of the side plate and the firing pin retained in the passage by the side plate, substantially as and for the purpose described.

5. In a firearm, a frame comprising a block having a lengthwise passage opening through its front and rear faces, a firing pin 10 slidable in the passage, and a side plate having an upwardly extending portion arranged in the rear of the block, the passage being located so that its rear end is partly closed by the front edge of the upwardly 15 extending portion of the side plate and hence the firing pin is retained in the passage by the side plate, substantially as and for the purpose specified.

6. In a firearm, a frame having a length- 20 wise passage opening through front and rear faces thereof, the passage having a rear cylindrical portion and a tapered front portion, a firing pin having a cylindrical body slidable in the cylindrical portion of the 25 passage, and a tapered portion movable in the tapered portion of the passage, the firing pin also including a rearwardly extending reduced portion at its rear end for receiving the blow of the hammer, and a side plate

having an edge portion thereof arranged to extend across and partly close the rear end of said passage and coact with the rear face of the body of the firing pin, to prevent displacement of the firing pin, the reduced rear end of the firing pin extending in the rear 35 of said edge portion, substantially as and for the purpose specified.

7. In a firearm, a frame having a length- 40 wise passage opening through its front and rear faces, a firing pin slidably fitting the passage and having a rearwardly extending reduced portion outside of the passage for receiving the blow of the hammer, and a side plate arranged so that an edge portion thereof extends across the rear end of the 45 passage and coacts with the body of the firing pin to normally prevent the firing pin from displacement, substantially as and for the purpose set forth.

In testimony whereof, I have hereunto 50 signed my name in the presence of two attesting witnesses, at Fulton, in the county of Oswego, in the State of New York, this 26th day of Feby. 1913.

ARTHUR P. CURTIS.
